UNITED STATES PATENT OFFICE.

HERBERT W. MOAK, OF ONEONTA, NEW YORK.

WRENCH.

1,064,361.

Specification of Letters Patent: Patented June 10, 1913.

Application filed September 9, 1912. Serial No. 719,409.

To all whom it may concern:

Be it known that I, HERBERT W. MOAK, a citizen of the United States, residing at Oneonta, in the county of Otsego and State 5 of New York, have invented certain new and useful Improvements in Wrenches, of which the following is a specification, reference being had to the accompanying drawings.

10 This invention relates to wrenches and more particularly to the class of monkey wrenches.

The principal object of the invention is to provide a wrench of the above stated character in which the movable jaw can be readily and quickly adjusted to any desired position.

Another object of the invention is the provision of a monkey wrench embodying a 20 movable jaw which has connected thereto a rack bar movable in a slot formed within the wrench shank and a collar mounted upon the stem of the shank and provided with pawls for engagement with the rack bar 25 whereby the movable jaw may be adjusted to any desired position.

A further object of the invention is the provision of a wrench of the above stated character comprising a movable jaw provided with a pair of rack bars, a collar slidably mounted upon the stem of the ratchet shank and provided with pawls for engagement with the rack bars, and an adjustable ferrule threadedly mounted upon the stem 35 whereby an additional or finer adjustment may be had after the movable jaw has once been set in adjusted position by moving the collar longitudinally of the stem.

A still further object of the invention is 40 the provision of a wrench of the above stated character, the movable jaw of which is provided with a pair of rack bars arranged on opposite sides of the wrench shank and movable in longitudinal grooves, 45 the teeth of one rack bar being finer or smaller than those of the other, whereby either one or both of the pawls carried by the collar will positively engage one of the rack bars.

50 A still further object of the invention is the provision of a wrench of the above stated character which will be cheap and inexpensive to manufacture, durable and substantial in design and one which can be

readily manipulated to adjust the same to 55 any desired position.

With these and other objects in view as will appear as the description proceeds, the invention comprises the various novel features of construction, combination and arrangement of parts as will be more fully described hereinafter and set forth with particularity in the appended claims.

Referring to the drawings Figure 1 is a side elevation of my improved wrench; Fig. 65 2 is a longitudinal sectional view taken on the line 2—2 of Fig. 1; Fig. 3 is a section taken on the line 3—3 of Fig. 2; and Fig. 4 is a detail view of a modified form of stationary and movable wrench jaws. 70

Referring more particularly to the drawings, the numeral 1 indicates the stationary jaw of my improved wrench and 2 the shank thereof which is provided at its opposite end with a suitable handle 3, which latter 75 is securely held upon the reduced end or the stem 4 of the shank 2 through the medium of a nut 5, threadedly connected to the lower end of the stem. The shank 2 is provided in its opposite side faces with longitudinally extending grooves 6 in which are arranged for sliding movement, the rack bars 7 and 8, the teeth of the rack bar 8 being finer or smaller than those of the bar 7 for a purpose that will presently appear. 85 A movable jaw 9 is slidably mounted upon the shank 2 of the wrench and has connected thereto the rack bars 7 and 8 through the medium of pins or screws 10.

The stem 4 of the shank has slidably arranged thereon a collar 11 which carries a pair of pawls 12 and 13 adapted to engage the rack bars 7 and 8 to hold the latter together with the movable jaw in any desired adjusted position. This collar 11, as clearly 95 shown in Fig. 3 of the drawings, is provided centrally with opposing recesses 14 into which slidably fits the shank 2 so that the collar will be prevented against radial movement upon the shank. The opposite 100 end portions of the collar are provided with recesses 15 in which are pivotally mounted the pawls 12 and 13 respectively. These pawls are pivoted intermediate of their ends as at 16 and are provided at their upper 105 ends with thumb engaging and lateral projections 17 and have their lower ends bent laterally to provide offset portions 18 which

are adapted to support the lower ends of the leaf springs 19. These springs 19, in this instance, are shown to be composed of two leaves secured together at their lower ends and bowed outwardly at their upper ends to provide forked or bifurcated upper spring ends. As clearly shown, the outer ends of the springs 19 bear against the pawls beyond their pivot and against the adjacent 10 side wall of the recesses 15. From this construction it will be apparent that the movable jaw may be adjusted longitudinally upon the shank of the wrench whereby either one or both of the pawls will 15 positively engage one or both of the rack bars for holding the movable jaw in the desired adjusted position.

The outer end portion of the stem 4 is threaded for a short distance as shown at 20 and has arranged thereon an adjustable ferrule 21 which latter, as shown in Figs. 1 and 2 of the drawings, is arranged below and adapted to support the collar 11. After the movable jaw has been adjusted to position and it is found that a still further adjustment might be had, the ferrule 21 is revolved or screwed upon the stem 4 so as to cause the collar 11, rigidly connected with the rack bars of the movable jaw, to move 25 upwardly upon the stem to secure this desired additional finer adjustment. As shown in Fig. 1, stop shoulders 22 are formed by the reducing of the shank 2 to form the stem 4. These stop shoulders 22 serve to 30 limit the upward movement of the collar 11.

In the operation of the wrench, the adjustable ferrule 21 normally rests upon the outer end of the handle, the collar 11 normally resting upon the ferrule so that when 40 it is desired to use the wrench, the movable jaw can be adjusted longitudinally of the shank to the desired position when, if found necessary, a further adjustment may be had by screwing the ferrule up upon the same 45 so as to cause the collar 11 to move outwardly carrying the rack bars and the movable jaw connected thereto.

In Fig. 4 is shown a modified form of the wrench in which the stationary jaw 1 is provided in its active face with teeth 23. The inner or movable jaw is also provided with teeth 23, which together with those of the stationary jaw serve to firmly grip and engage a pipe when it is desired to turn the 55 same. This construction as shown in Fig. 4, provides a very efficient and durable pipe wrench. However, I desire it to be understood that I am not limited to the exact form and design above described, but that 60 minor changes in the construction may be made when desired.

Having thus described the invention, what is claimed is:

1. A wrench comprising a shank provided 65 with a stationary jaw on one end and a

handle on the other end thereof, a movable jaw mounted upon the shank and provided with rack bars, a collar being formed with recesses mounted upon the shank, and spring pressed pawls disposed in the recesses in 70 said collar and adapted to engage said rack bars to hold the movable jaw in adjusted position.

2. A wrench comprising a shank formed with a stationary jaw on one end and a 75 handle on the opposite end, a movable jaw mounted thereon, rack bars carried by said jaw, a collar mounted upon the shank, means carried by the collar adapted to engage said rack bars to hold the movable jaw in an 80 adjusted position, and means disposed on said shank inwardly of said collar for adjusting said collar longitudinally of the shank to secure additional adjustment of the movable jaw.

3. A wrench comprising a shank provided on one end with a stationary jaw and a handle upon the opposite end, a movable jaw mounted on the shank, rack bars carried by the movable jaw, a collar mounted 90 upon the shank, means carried by the collar adapted to engage said rack bars, and an adjusting ferrule mounted upon the shank inward of said collar.

4. A wrench comprising a shank provided at one end with a stationary jaw, and a handle at the opposite end, a movable jaw mounted upon the shank, rack bars carried by the movable jaw, the teeth of one rack bar being smaller than those of the other, a 100 collar carried by the shank, and pawls carried by the collar for engagement with said rack bars.

5. A wrench comprising a shank having a stationary jaw at one end and a handle at 105 the opposite end, said shank being provided in its opposite side faces with longitudinal grooves, a movable jaw arranged upon the shank, rack bars secured to the movable jaw and disposed in said grooves 110 for sliding movement, the teeth of one rack bar being smaller than those of the other, a collar arranged upon the shank, and pawls carried by said collar and adapted to engage 115 said rack bars.

6. A wrench comprising a shank provided at one end with a stationary jaw and a handle at the opposite end, a movable jaw mounted upon the shank, rack bars carried by the movable jaw, the teeth of one bar being smaller than those of the other, a collar carried by the shank, pawls carried by the collar and adapted to engage said rack bars, and a ferrule adjustably connected to 120 the shank inward of the collar for adjusting the latter longitudinally of the shank.

7. A wrench comprising a shank provided at one end with a stationary jaw reduced at its opposite end to provide a stem, a handle mounted upon said stem, said shank being 125

provided in its opposite longitudinal faces with grooves, a movable collar arranged upon the shank, rack bars carried by the movable jaw and disposed within said 5 grooves for longitudinal movement, the teeth of one rack bar being smaller than those of the other, a collar mounted upon the stem of the shank for longitudinal adjustment thereon, and a ferrule threadedly 10 mounted upon the stem inward of the col-

lar for adjusting the latter longitudinally of the stem to secure an additional adjustment.

In testimony whereof I hereunto affix my signature in the presence of two witnesses. 15
